UNITED STATES PATENT OFFICE.

HARRY E. LEE, OF OAKLAND, CALIFORNIA.

RULE.

1,150,277.

Specification of Letters Patent. Patented Aug. 17, 1915.

Application filed October 5, 1914. Serial No. 865,176.

To all whom it may concern:

Be it known that I, HARRY E. LEE, a citizen of the United States, residing at Oakland, in the county of Alameda and 5 State of California, have invented new and useful Improvements in Rules, of which the following is a specification.

An object of the invention is to provide a rule particularly of the type generally 10 known as carpenters' or pocket rules, and which is so arranged and constructed that it provides accurate continuous straight edges when the rule is open, the rule having its sections adjustable to various angles whereby 15 one section can be temporarily held at an angle to the other section.

Still further objects of the invention reside 20 in a rule embodying various improvements over a rule construction set forth in United States Patent No. 687,432, granted to me November 26, 1901.

The invention contemplates, among other 25 features, the provision of a rule in which the sections can be arranged in alinement to provide continuous straight edges or brought into angular relation and in which the angular relation of sections can be relatively 30 but temporarily held for the purpose of securing a desired measurement or angle, said sections being relatively foldable so that the rule can be easily carried in the pocket.

In the further disclosure of the invention 35 reference is to be had to the accompanying drawings, constituting a part of this specification, in which similar characters of reference denote corresponding parts in all the views, and in which:

Figure 1 is a fragmentary plan view of 40 the rule, showing the sections in angular relation; Fig. 2 is a fragmentary plan view of the rule, showing the sections in alinement; Fig. 3 is a fragmentary plan view of the rule showing the sections relatively 45 folded; Fig. 4 is a fragmentary sectional view of the rule, showing the means for temporarily holding the sections in angular relation, the sections in this view being shown in alinement; Fig. 5 is a similar view 50 showing the sections in angular relation, one of the locking members being shown in section; Fig. 6 is a vertical sectional view taken on the line 6-6 in Fig. 5; and Fig. 7 is a vertical sectional view taken on the line 7-7 55 in Fig. 5.

Referring more particularly to the views,

the rule body is indicated by the numeral 15 and consists of similar sections 16, these sections being hingedly related as and for a purpose that will be hereinafter more fully 60 disclosed. Each of the sections at its inner end carries a substantially circular disk or boss 17 provided with a diametrical groove or channel 18 in which is arranged a plurality of opposed members 19 pressed relatively 65 outward by an expansible helical spring 20 arranged between the members and having its ends seated in openings 20^a in said members. A plate 21 has openings 22 therein, one opening being provided for 70 each disk 17 and through which the disk extends, said plate connecting the sections 16, as will be readily seen, it being of course understood that there is a disk 17 provided for each section, with corresponding members 75 19 in the groove-like channel 18 of each disk.

The plate 21 is provided with spaced notches 23, each of which is formed to provide a curved wall and a straight wall, with 80 the straight wall forming a stop 24, as will be clearly seen by referring to the views. The members 19 upon each disk, operated upon by the spring 20, are adapted to have their outer ends project into the notches, 85 said notches and members, however, being arranged so that when one member of each disk is in one of the notches, the other member of the disk will be out of the other notch. The free ends of the members are 90 furthermore formed with a curved edge to conform to the curvature of the wall of each notch so that when a swinging movement is imparted to one of the sections the section can be hinged upon the plate in both 95 directions to a limited extent, the limit of movement of each section relatively to the plate being determined by the position of the section with respect to the plate and its angular relation thereto and whereby, when 100 the section is alined with the plate, said section cannot be swung outwardly beyond its normal alinement with the plate, this being prevented by having the straight edge of one of the members 19 abutting against the stop 24 when the member extends into the notch in the plate which has its wall forming the stop 24.

Now referring to Fig. 4 we will assume 110 that the sections have been relatively alined and are in alinement with the plate. It will now be clearly seen that the right hand sec-

tion cannot be swung upwardly or outwardly and out of alinement with the other section and the plate for the reason that one of the members in the disk of the section bears against the stop 24 of the plate. So also with the other section and which has reached its limit of outward or upward movement. It will be seen, however, that either the left or right hand section can be swung inwardly so that one section will lie at right angles to the other and as shown in Fig. 5 the left hand section is shown swung inwardly at right angles to the right hand section, this being possible for the reason that one of the members on the disk of the left hand section can be moved out of the notch in the plate when the section is swung inwardly on account of the curvature of the wall of the notch and the curvature of the free end of the member. It will be seen, however, that when the left hand section has been swung at right angles to the right hand section as shown in Fig. 5, the other member on the disk of the left hand section will swing into the other notch in the plate and thus the sections 16 will be temporarily locked at right angles to each other, although it will be clearly seen that the right hand section is still capable of being swung inwardly due to the fact that one of its members 19 carried upon its disk can ride out of the notch into which it normally extends until the other member on the disk of that section is received in the other notch in the same manner in which the members on the disk of the left hand sections are arranged. When this is done the two sections will be relatively folded as shown in Fig. 3, and thus by referring to the views it will be seen that the two sections can be moved from their relatively folded position to the relatively rectangular right angle position shown in Fig. 1 or to the open position shown in Fig. 2, at which position they will be in perfect alinement. It will of course be understood that the sections need not be necessarily moved at right angles to each other for, as shown in Figs. 1 to 3, one of the sections, namely, the left hand section, is provided with a protractor scale 25 associated with an indicator 26 on the left hand section and whereby the sections can be relatively moved to any desired angle, although they are shown in Fig. 1 as being temporarily located in relatively right angle position.

Referring to Fig. 2 it will be clearly seen that when the sections are in alinement the inner edge 27 of the plate 21 forms a continuation of the inner straight edges 28 of the sections, thus doing away with the usual recess which is formed in the ordinary rule at the juncture of the sections. It will be further clearly seen that when the sections are open to lie in alinement and the rule is

subsequently raised to a vertical position, the upper section will not collapse downwardly upon the lower section, but will be held in its open position by one of the locking members 19 engaging one of the stops 24 of the plate which hingedly connects the section, the lock, however, being but a temporary lock in that one section can be swung inwardly toward the other by simply exerting a pressure upon the outside edge of the section and which pressure is transverse to the length of the section.

With a rule of the character described, the collapsing of the rule when the sections are relatively open and in alinement is prevented and, furthermore, the sections can be angularly related and temporarily locked in their angular relation, being also movable into any desired relative angularity as mentioned. The plate connecting the sections furthermore acts as a reinforcement at the point of hinging of the sections and thus it will be seen that the rule set forth will be of a more durable construction and greater strength than the ordinary rule having the usual hinge sections.

I am aware that rules have been used heretofore which can be angularly related and locked in an angular relation, but generally in these instances a longitudinal movement of one of the sections is necessary in order to effect the temporary locked relation of the sections, the longitudinal movement of one of the sections being followed by a swinging movement in order to accomplish the desired result. In my device, however, it is only necessary to swing one section relatively to the other without initially moving one of the sections longitudinally of itself, and thus it will be seen that with a rule of the character described the sections composing the rule being hinged in a novel manner can be relatively folded to lie adjacent each other; unfolded to relatively aline or partially folded to be temporarily locked at right angles or relatively folded at right angles to each other within an arc of one hundred and eighty degrees.

Having thus described my invention, I claim:

1. In a rule, a plurality of similar sections, a disk on each section and provided with a groove, a plate in hinged relation to the disks and swingingly connecting the sections, said plate being provided with pairs of notches, and diametrically opposed spring-actuated locking members in the groove of each disk and associated with each pair of notches whereby said sections can be temporarily locked in angular relation.

2. In a rule, a plurality of sections, a plate hingedly connecting said sections and having pairs of notches, and a diametrically opposed spring-actuated pair of locking members for each section and associated

with a pair of the notches to extend therein and temporarily lock the sections in angular relation.

3. In combination with a plurality of 5 swingingly connected sections capable of being moved into or out of relative alignment, a plate having spaced notches and effecting the swinging connection between the sections, and opposed spring-actuated 10 means for each section and adapted to extend into the notches of the plate to temporarily lock the sections in angular relation.

4. In combination with a plurality of 15 swingingly connected sections capable of being moved into or out of relative alignment, a plate having spaced notches and effecting swinging connection between the sections, and opposed locking members for 20 each section and adapted to extend into the

notches of the plate to temporarily lock the sections in angular relation.

5. In combination with a plurality of swingingly connected sections capable of being moved into or out of relative alignment, 25 a plate having spaced notches and effecting swinging connection between the sections, and opposed locking members for each section and adapted to extend into the notches of the plate to temporarily lock the 30 sections in angular relation, one of said locking members extending into one of the notches when the other member is removed from the other notch.

In testimony whereof I affix my signature 35 in presence of two witnesses.

HARRY E. LEE.
